UNITED STATES PATENT OFFICE.

GEORGE J. DELFELD AND BRITTON W. SWAIN, OF SAPULPA, OKLAHOMA.

OIL BURNER.

Application filed August 17, 1926. Serial No. 129,770.

This invention relates to an improved oil burner which is especially, but not necessarily adapted for use with locomotive boilers, and it has more particular reference 5 to a burner of this kind which has been especially designed for consuming comparatively heavy crude oils and analogous fuels.

Our principal aim is to provide an especially constructed burner which is such as 10 to minimize the formation of carbon deposits, not only on the burner itself but upon the walls of the fire box in which it is used.

An equally important aim is to conserve 15 the consumption of fuel, to reduce vibration, to substantially eliminate the objectionable drumming noise which usually accompanies burners of this class, and to promote good combustion by providing proper atomization of the fuel charge.

20 Moreover, we aim to provide a burner which is of a construction to insure smooth burning, one which is exceptionally simple in construction and inexpensive to both the manufacturer and the user, the same being 25 in the form of a one-piece construction to avoid dislocation of parts and to render the construction exceptionally compact and convenient.

Other features and advantages of the 30 invention will become apparent from the following description and drawing.

In the accompanying drawing:—

Figure 1 is a central longitudinal section 35 through a burner constructed in accordance with the present invention.

Figure 2 is a cross section taken approximately upon the plane of the line 2—2 of Figure 1.

Figure 3 is a bottom plan view of the 40 burner, and

Figure 4 is a front elevation of the same.

In carrying out the invention, a single 45 metal casting is provided and is formulated to produce an oil conduit 1, an atomizer conduit 2, and a supporting and attaching base or bracket 3. The major portion of these conduits indicated by the reference characters 4 and 5 respectively are cylindrical in cross section. At one end screw threads 6 and 7 are provided for connection of suitable supply pipes (not shown). Beginning 50 at about the point 8, these conduits are gradually widened and simultaneously flattened to formulate discharge nozzles. In both instances, the nozzles are of oblong shape or represent a parallelogram in end elevation.

The oil nozzle is represented by the reference character 9 and the air and steam or atomizing nozzle is represented by the reference character 10. As shown better in Figure 4 60 the oil nozzle 9 is provided with an elongated discharge slot 11 of predetermined proportion. The discharge nozzle 10 is likewise provided with an elongated discharge slot 12, but it will be seen that this is wider 65 than and narrower than the slot 11. These proportions are regarded as essential for proper operation. As shown better in Figure 1, the oil nozzle overhangs or extends beyond the atomizing nozzle 10, and a groove 70 13 is formed in the under side of the extending portion.

In connection with the device it is to be stated that the discharge nozzle of the oil conduit must be wider than the general outline of the body portion. The discharge passage itself must extend inwardly or back a short distance and have the same general shape as the oblong nozzle, and then gradually merge into the cylindrical outline of 80 the body portion of the tube, thus making a perfect breaker for the oil, concentrating the same, and insuring proper mixture and expulsion. Of course, the wall on the interior must be perfectly smooth and free from all 85 obstructions. The atomizer tube is of the same general outline with the exception of the outlet passage which is somewhat longer and narrower in order to insure the discharge of a substantially flat sheet of air 90 or steam. By permitting the atomizer nozzle to terminate short or inwardly of the complementary oil nozzle, a space is provided for the oil groove, thus preventing oil from coming down beneath and entering the 95 atomizer nozzle. Instead whatever oil that runs in this manner will accumulate in the groove.

It is maintained that a burner of this design will preserve the interior lining of the 100 fire box which is generally composed of fire brick walls, thus eliminating heavy cost of applying new bricks and other forms of lining. There are no removable parts to get out of order. The burner may be easily 105 cleaned from either end, and taking these advantages into consideration with those previously given, it is believed that this particular construction is superior over known marketed and patented burners. It is also 110 thought that by considering the description in conjunction with the drawing a clear un-

derstanding of the construction and operation of the burner will be had. Consequently, a more detailed description is believed unnecessary.

5 Having thus described the invention, what we claim is:—

An oil burner of the class described comprising a single metal casting having an oil passage and an atomizing passage extending longitudinally therethrough, the major portions of said passages being cylindrical and merging at their outer ends into widened and flattened passages providing restricted discharge nozzles, the air nozzle disposed be-

low said oil nozzle and terminating in inwardly spaced relation thereto, the overhanging portion of said oil nozzle being formed in its under side with a transversely disposed oil collecting groove and the discharge openings of said nozzle being of oblong configuration, the oil discharge opening being wider and shorter than the complementary air discharge opening.

10 In testimony whereof we affix our signatures.

GEORGE J. DELFELD.
BRITTON W. SWAIN.
